UNITED STATES PATENT OFFICE.

MITCHEL C. GARDNER, OF ROCHESTER, NEW YORK.

IMPROVEMENT IN CAR-COUPINGS.

Specification forming part of Letters Patent No. 40,833, dated December 8, 1863.

To all whom it may concern:

Be it known that I, MITCHEL C. GARDNER, of the city of Rochester, county of Monroe, and State of New York, have made and invented a certain new and Improved Self-Acting Coupling for Railroad-Cars; and I do hereby declare the following to be a full and accurate description of the same, reference being had to the accompanying drawings, making part of this specification, and to the letters of reference marked thereon, same letters referring to like parts in both figures.

The nature of this invention consists in so constructing the buffer-head that it shall be certainly and securely self-acting, and this not only while the various parts are new, but after the holes have become worn and the pins and links bent and out of shape; and although the problem thus presented for solution is a difficult one, it will be found that a coupler constructed after the manner to be presently described satisfies every condition.

My buffer-head or coupling consists, primarily, of the wrought-iron draw-bar D and cast-iron blocks B, which are connected together by means of a wrought-iron band shrunk on after the manner described in the patent issued to me on the 27th day of April, 1858.

In order to produce a reliable self-acting coupling, in which the ordinary pin and link may be used, (a condition absolutely necessary, as it is often requisite to mingle cars with the new coupling in the same train with cars provided with the ordinary arrangement,) the following points must be attained:

First. The pin must be securely held in an elevated position until released by the link. Blows and jarring must have no effect upon it.

Secondly. The pin must be guided to the hole in the lower plate of the buffer-head without any reliance being placed upon the guiding action of the hole in the upper plate. This is absolutely necessary, as the pins are often bent, worn, and otherwise injured.

Thirdly. The link must be so held when in place in one coupler that it will infallibly enter the other.

Other points are of course necessary, but

these are the essential requisites to be aimed at. These are all attained in my coupler by the following means: The cast-iron blocks forming the funnel-shaped head of the coupler contain not only the usual holes for the pin and slot for the link, (which latter is prevented from being driven too far into the coupler by means of properly-adjusted stops,) but also, in addition to these, two holes or grooves, one in each block, the axis of these holes lying in a plane at right angles to the line of draft, and ascending outward from the slot which receives the link at about an angle of forty-five degrees, as is shown in Fig. 1, which is a front elevation of my buffer-head, the pin, the balls, and the holes for the motion of the latter being shown in red lines.

It is now obvious that if a link should be arranged as shown in the right-hand buffer of Fig. 2, and should be driven against the left-hand one, it will separate the balls upon which the pin rests, and will allow the latter to drop; but as the pin falls no faster than the balls separate to make way for it, it is evident that the point of the pin will be guided in an accurately vertical direction until it falls into the hole in the bottom plate of the buffer-head. The accuracy with which this is effected, even when the pin is small and crooked, must satisfy even the most skeptical that the problem has been solved; and the buffer-head costs no more than those of ordinary construction, while it is liable to but very slight deterioration from tear and wear, and at the same time allows the wrought-iron portion (the most expensive part) to be used over and over again.

Having thus described my invention, what I claim therein as new, and desire to secure by Letters Patent, is—

The method herein described of supporting the pin P by means of the balls C, moving in holes or grooves at right angles to the line of draft, the whole operating in the manner and for the purpose substantially as described.

M. C. GARDNER.
